DESIGN FOR A FINGER SUPPORT FOR
MANICURING OPERATIONS

Raymond J. McKee, Brooklyn, N. Y.

Application November 6, 1946, Serial No. 134,557

Term of patent 3½ years

(Cl. D86—10)

To all whom it may concern:

Be it known that I, Raymond J. McKee, a citizen of the United States, residing at Brooklyn, in the county of Kings and State of New York, have invented a new, original, and ornamental Design for a Finger Support for Manicuring Operations, of which the following is a specification, reference being had to the accompanying drawing, forming part thereof.

Figure 1 is a plane view of a finger support for manicuring operations showing my new design; Figure 2 is a side elevation; and

Figure 3 is an end view of a finger support for manicuring operations shown in Figures 1 and 2.

I claim:

The ornamental design for a finger support for manicuring operations, as shown.

RAYMOND J. MCKEE.
